WHEEL MOUNTING DEVICE

Giovanni Bergonzo, Turin, Italy

Application October 12, 1950, Serial No. 189,717
In Italy October 13, 1949

2 Claims. (Cl. 301—9)

1

This invention relates to means for fastening vehicle wheels to their rotating supports and provides a device permitting quick and easy fastening and unfastening.

The device according to this invention comprises cooperating means carried by the wheel and its support, adapted to prevent relative angular displacements between the said parts, and a coupling member containing a rotatable element which, by simultaneously co-operating with elements carried by the wheel and its support, prevents their relative axial displacement.

The rotatable element is rotated by effect of spring means previously tensioned during disassembly of the wheel, said means being released by depressing a push-button.

Further features and advantages of this invention will appear from the following description, in which reference is made to the accompanying drawing, which shows diagrammatically by way of example a construction thereof:

Figure 1 is a radial part section of a wheel provided with the improved fastening;

Figure 2 is a section on the line II—II of Figure 1; and

Figures 3 and 4 are sections on lines III—III and IV—IV of Figure 2, respectively.

A denotes the wheel drum to which a flange 1 is secured by means of nuts 2 screwed on bolts 3 which are provided on the drum and project therefrom.

The wheel B is riveted at 4 to an annulus 5 which fits by means of a conical surface 6 an associated conical surface on the flange 1, with respect to which it is kept from rotating by clutch teeth 5a meshing with corresponding teeth 1a on the flange 1. At its opposite end said flange terminates with a circular set of sectors 11 flanged at 12 for the reasons set forth hereinafter.

The annulus 5 is formed outwardly with a further conical surface 7 against which is pressed an annulus 8 of C-shaped section forming an annular chamber 9. The inner face of the annulus 8 is formed with four slots 10 through which four sectors 11 on the flange 1 bent at their ends at 12 reach within annular chamber 9. The inner surfaces 13 of the ends 12 are tapered, as shown in Figure 4, and are acted upon by corresponding tapers 15 on teeth 16 on an annulus 17 located in the annular chamber and rotated through small angles by means of a spanner acting on the polygonal surface 18.

The teeth 16 are of a width such as to fit with a slight clearance in the hollows between the ends of the sectors 11.

2

Two coiled tension springs 19 are secured at one end to the annulus 17 by screws 20 and at their other end to the annulus 8 by means of screws 21, and are enclosed within the annular chamber 9.

A cover 22 secured to the annulus 8 by means of screws 23 retains the annulus 17 within the annular chamber 9 in the annulus 8.

As shown in Fig. 3, a stop piston 24 is axially displaceable in a bore 25 in the annulus 8 and in a further bore 26, coaxial with the former, in the cover 22.

The piston is formed with a recess 27 by which it is retained on one of the teeth 16. A tension spring 28 abuts at one end a plate 29 bearing on the tooth 16 and at its other end shoulder 30 on the piston 24.

The tooth 16 is formed with a semi-circular recess 31 engaging the end 32 of the piston 24 under the action of the spring 28 when it comes in register therewith.

The device operates in the following manner: When the wheel is disassembled, the above-mentioned parts form the following three separate units.

(a) Drum A with flange 1.

(b) Wheel B with annulus 5.

(c) Assembly of annuli 8 and 17 in a relative position such that the end 32 of the piston 24 is engaged by the semi-circular recess in the annulus 17. In this position the springs 19 are tensioned.

In order to fasten the wheel B on the drum A, the annulus is fitted on the flange 1 causing the teeth 1a and 5a to engage together.

Thereupon, the assembly (c) is fitted into the annulus 5, the teeth 16 being staggered with respect to the slots 10 in order to allow the ends 12 of the sectors 11 to reach between the teeth 16.

By depressing the head of the piston 24 to remove it from the recess 31, the springs 19 displace the annulus 17 angularly with respect to the annulus 8. The teeth 16 are brought underneath the flanges 12 of the sectors 11, causing the tapers 13 and 15 to slide relatively to each other till the set of teeth 16 co-operating with the teeth 12 push the annulus 8 against the conical surface 7 and the annulus 5 against the conical surface 6, thereby locking the wheel B on the drum A.

In order to disassemble the wheel B the annulus 16 is angularly displaced by acting on the polygonal surface 18 by means of a suitable spanner or otherwise. The set of teeth 16 come into register with the hollows between the teeth 12.

In this position, the piston 24 is in front of the recess 31 and is caught therein under the action of spring 28 which retains the annulus 17 in this position. The assembly (c), which retained the wheel on the drum, may now be axially withdrawn, whereupon the wheel may be removed from the conical surface 6 on the drum.

What I claim is:

1. In combination, a rotating support provided with clutch teeth, a wheel coaxial with said support and provided with dog teeth complementary to the former, a circular set of flanged sectors fixedly connected with said support and coaxial therewith, a bush fixedly connected with the wheel and arranged in such manner as to surround said circular set of flanged sectors; a first annular member wedged within said bush, said annular member forming an annular chamber provided with bottom openings through which said flanged sectors on the support enter into said chamber, a second annular member rotatably arranged in said annular chamber and provided with flanged sectors adapted to become wedged between the first mentioned flanged sectors and the bottom of the annular chamber on rotation of said second annular member through an angle smaller than 360° , spring means arranged between said two annular members for automat-

ically producing said rotation, means provided on said second annular member for rotating said member against the action of said spring means and a spring-pressed locking bolt for blocking said rotatable annular member with respect to said first annular member as said flanged sectors are in disengaged position.

2. Device as claimed in claim 1 in which the rotatable annular member ends externally by a surface having a polygonal outline in order to rotate from the outside said member against the action of said spring means.

GIOVANNI BERGONZO.
